UNITED STATES PATENT OFFICE

RUDOLPH E. SNYDER, OF DENVILLE, NEW JERSEY

GARAGE VENTILATING MEANS

Application filed October 18, 1932. Serial No. 638,379.

This invention relates to an unusual structural assembly expressly designed to serve as ventilating means for an automobile garage, particularly the home or domestic type.

5 A consensus of public opinion undeniably indicates that there is a dire need for practical and expedient means to guard against persons becoming asphyxiated and overcome by deadly exhaust gases such as frequently 10 accumulate in closed garages. Undoubtedly, the average motorist knows that it is hazardous to run the motor in a garage with the doors closed. Despite this fact there are 15 many fatal casualties from this cause every year.

With the foregoing disastrous results in mind, I have discovered the need for an automatically operable garage ventilating means such as will serve to effectively aerate 20 the garage even if the doors are closed for want of comfort in cold weather.

I accomplish the requisite results through the instrumentality of appropriately co-ordinated closures for ventilating openings,

25 wherein the ensemble of closures is united through the agency of suitable operating connections, whereby to permit said closures to swing to open ventilating position in a simultaneously and desirable manner.

30 In carrying the inventive conception into actual practice, I have adopted effectively co-related devices such as mutually co-operate to provide a sensible, simple, fool-proof structural assembly which will fulfill the requirements in a gratifying and satisfactory manner.

35 In the accompanying drawings, wherein like numerals are employed to designate like parts throughout the same:

40 Figure 1 is a view in section and elevation showing a conventional garage equipped with the improved ventilating means.

45 Figure 2 is a vertical section on the plane of the line 2-2 of Figure 1.

Figure 3 is an enlarged fragmentary detail sectional and elevational view showing the automatically operable trip means.

50 Figure 4 illustrates a manually released holding latch.

Figure 5 is an enlarged detail section tak-

en approximately on the plane of the line 5-5 of Figure 1.

In the drawings, in Figure 1, the garage which may be of any conventional design or construction is generally denoted by the 55 numeral 6. The garage here shown is of the so-called portable sheet metal type. The garage doors 7 are ordinary hingedly mounted horizontally swinging companion doors. 60 The numerals 8 designate panels which, in accordance with the present invention, are provided near their lower end portions with suitably framed ventilating openings 9.

In this connection I call attention to a 65 complemental hingedly mounted closure plate 10 normally held in closed position through the agency of suitable spring means 11 (see Figure 5). At its lower swingable end, the door is provided with a rigid lifting arm 12 to which an elevating cable 13 is 70 connected. These openings 9 and complemental plates 10 form what may be designated as auxiliary vents or ventilating devices.

The main ventilating device comprises a 75 window structure 14 mounted in the upper front wall of the garage structure in spaced relation to the overhanging roof as shown in Figure 2. This main ventilator comprises 80 an appropriate diamond-shaped set-in frame 15 fashioned to accommodate the correspondingly shaped ventilating window 16 mounted on horizontal pivots 17. The numeral 18 designates a coiled return spring attached to the lower swingable end of the window 85 and to an anchoring bracket 19.

The numeral 20 in Figure 2 designates a holding clip of the cam acting type carried by the upper swingable edge portion of the panel or window and this is adapted to 90 engage back of a retention shoulder 21 formed on the free end portion of a gravity lowered latch 22. The latch is pivotally mounted as shown and is aided in its return to a normal position through the instrumentality of appropriate spring means 23.

In this connection I call attention to a 95 cable 24 attached to the free swingable end of the latch and trained over a pulley 25 and having its depending end portion pro-

vided with a finger ring 26 located within convenient reach of the occupant of the garage.

I next call attention to the door actuated 5 operating means for automatically swinging the window or panel to open position. This comprises a flexible element or cable 27 which is attached to the clip 20 and in turn attached to the long arm of a bellcrank 28. 10 The bellcrank is pivotally mounted as at 29 between the furcations 30 of a bifurcated hanger 31 rigidly supported in place.

Between the furcations is an anti-friction 15 fulcrum roller 32 for the main actuating link 33. The link terminates in a headed extremity which may be designated as a catch 34 shaped to engage a keeper 35 of corresponding form carried by the adjacent swingable doors 7 as shown in Figures 2 20 and 3.

Normally, it is understood that the auxiliary closure plate 10 as well as the window 16 are closed. At this time, and assuming 25 that the garage doors are also closed, it is evident that the catch 34 is engaged with the keeper 35. Hence, as the garage doors are swung to open position, the keeper 35 serves to exert an endwise pull on the link 33. Manifestly, this rocks the bellcrank 28 30 which through the instrumentality of the cable 27 swings the window 16 to tilted open position against the tension of the spring 18.

When the bellcrank swings down to the full-line position shown in Figure 2, the link 33 fulcrums or rides on the anti-friction roller 32, thus permitting the catch 34 to automatically disengage from the keeper 35. In proper timed relation, the clip 20 rides 40 down against the latch 22 and engages behind the shoulder 21 to sustain the window 16 in this open state.

Inasmuch as the aforesaid cables 13 are trained over suitable pulleys 36 and operatively connected with the panel 16 as shown 45 in Figure 1, it is evident that the closures 10 are also lifted to open position and held in such positions until the latch 22 is released.

Thus, even though the garage doors are 50 again accidentally closed, the ventilators are still open. In fact, the only way that the ventilators can be returned to their normal closed position is to attend to this voluntarily and manually by releasing the latch 22. 55 This is simply done by catching hold of the finger ring 26 and pulling down on the cable 24.

It is thought from the foregoing description that the advantages and novel features 60 of the invention will be readily apparent.

It is to be understood that changes may be made in the construction and in the combination and arrangement of the several parts provided that such changes fall within 65 the scope of the appended claims.

I claim:

1. In a structure of the class described, in combination, a garage embodying swingably mounted doors, and having a ventilating opening above said doors, a ventilating window pivotally mounted in said opening, together with an operating connection between the window and one of said doors, whereby when the door is swung to open position, said ventilating window is automatically swung to its open ventilating position, and voluntarily operable manually controlled means for sustaining the window in its open position. 70

2. In a structure of the class described, in combination, a garage provided with hingedly mounted swingable doors, a main ventilating opening above said doors, a ventilating window pivotally mounted in said opening, said garage being also formed adjacent its lower portions with auxiliary ventilating openings and complemental closures therefor, operating connections between the auxiliary closures and window to permit said parts to operate automatically and in unison, and door actuated operating means for said window. 80 85

3. In a structure of the class described, in combination, a garage provided with hingedly mounted swingable doors, a main ventilating opening above said doors, a ventilating window pivotally mounted in said opening, said garage being also formed adjacent its lower portions with auxiliary ventilating openings and complemental closures therefor, operating connections between the auxiliary closures and window to permit said parts to operate automatically and in unison, and door actuated operating means for said window, a pivotally mounted 90 95 sustaining latch co-operable with the window to hold it in its open position, and manually manipulated release means for said latch. 100 105

4. In a structure of the class described, in combination, a garage, including a pair of companion hingedly mounted doors, having a main ventilating opening formed in a portion thereof above said doors, a pivotally mounted window co-operating with 110 said opening, a return spring for said window, a pivoted retaining latch, a cam acting clip carried by the window and engageable with said latch, a manually manipulated pull-cable for releasing the latch, and an 115 operating connection between the window and one of said garage doors. 120

5. In a structure of the class described, in combination, a garage including a pair of companion hingedly mounted doors, having a main ventilating opening formed in a portion thereof above said doors, a pivotally mounted window co-operating with 125 said opening, a return spring for said window, a pivoted retaining latch, a cam 130 135

acting clip carried by the window and engageable with said latch, a manually manipulated pull-cable for releasing the latch, and an operating connection between the window and one of said garage doors, including a pivotally mounted bellcrank, a flexible operating connection between the bellcrank and window, hangers for the bellcrank, a fulcrum anti-friction roller on said hanger,
5 a catch-equipped link connected with the bellcrank and co-operable with the roller, and a keeper carried by the adjacent door for co-operation with said catch.
10

In testimony whereof I affix my signature.
